UNITED STATES PATENT OFFICE.

CHARLES T. DAVIS, OF NEW YORK, N. Y.

PACKAGE.

1,387,839.

Specification of Letters Patent.

Patented Aug. 16, 1921.

Application filed March 9, 1920. Serial No. 384,565.

To all whom it may concern:

Be it known that I, CHARLES T. DAVIS, a citizen of the United States, and resident of New York city, in the county of Kings and State of New York, have invented certain new and useful Improvements in Packages, of which the following is a specification.

My invention relates to containers, and particularly to the type in which the nature 10 of the article inclosed therein may be ascertained without opening the package.

It is often desirable and sometimes necessary that an article which is packaged in a suitable protective container should remain 15 therein until actually used. This requirement, however, is difficult to reconcile with the necessity for permitting the purchaser or user to ascertain the nature of the packaged article.

20 One common solution of this difficulty is the employment of a transparent element in the container; but the materials from which such element must be made are utterly unsuitable for use in many types of package, 25 as well as in packaging certain types of articles, because of the fragility or other characteristic of the transparent materials known to those skilled in the art as suitable for this purpose.

30 An object of my invention is to provide a package so constructed that the nature of the article contained therein can readily be ascertained from the outside of the package without opening it, and without depending 35 upon the use of transparent or translucent material.

I accomplish this object broadly by employing, in the construction of the package, a material capable of receiving and retaining an impression of the article itself, the impression being visible from the outside of the package and forming a guide to the nature of the article in the package.

40 A further object is to employ such an impression-retaining material which is relatively strong, tough, and resistant to severe usage. In the specific embodiment disclosed, another object is to employ such a material that is resistant to the effects of moisture 45 or heat, or both.

Another object is to provide a package for surgical needles and similar articles which will insure the complete sterility of each needle when the package is opened.

50 While the necessity for thorough steriliza-

tion of instruments used in connection with operations is well-recognized and the necessary technique for attaining this result has been carefully developed, failure to follow the necessary steps therein results in imperfect sterilization. To avoid the danger of such failures, especially in connection with surgical needles, I have provided a convenient practical package which will preserve each needle in complete sterility up to the moment when it is actually needed. To accomplish this object, I prefer to employ a hermetically sealed package, which may be opened readily at the moment when the needle is needed, effectively preventing contamination thereof by careless preliminary handling.

A common method of sterilizing instruments, including needles, is to boil them in water just prior to use, and as several needles are ordinarily boiled for each operation, those not used are likely to rust, even though great care is taken in drying and packing them subsequent to boiling. Atmospheric dampness, particularly in the tropical climates, also provides a prolific cause of rust, making it difficult to maintain needles in the necessary polished, bright condition. Another object of my invention is to eliminate the danger of rust by providing a sealed package for surgical needles, in which they may readily be boiled in the usual way without contacting with the moisture of the sterilizing bath, thus permitting repeated boiling of a needle package without any danger of rusting the needle, the package being also adapted to protect the inclosed needle against external moisture of all kinds, regardless of how long the needle is kept before use and irrespective of climatic conditions.

Surgical needles are manufactured in a great variety of styles, varying both in size and contour, each being adapted to the needs and preferences of surgeons in performing particular operations. It is also customary to identify various sizes and shapes by style and size numbers. In the usual routine of preparing for an operation, the surgeon selects needles of the desired type and subjects them to a sterilizing process, such as boiling. This practice renders the provision of a suitable protective package particularly difficult, as such a package, in the ordinary well-known forms thereof, would

2
 prevent the surgeon from ascertaining the exact type of needle therein, except by direct inspection; and it will be apparent that reliance upon style numbers provides a fruitful source of mistakes. Furthermore, many standard types of package would be wholly inadequate to protect the needle against rust after repeated sterilization, as it is customary to select several needles for each operation, the result being that a needle is often sterilized several times before actually being used. It is obviously highly desirable to retain each needle in its package until it is required for use, after sterilization.

A primary object of my invention is to overcome these difficulties by providing a package of such a nature that the exact style of needle therein may be readily and directly ascertained without opening the package. I preferably accomplish this object by constructing the needle container from a material in which the outline of the inclosed needle may be impressed, permitting the surgeon to ascertain the style of needle at a glance.

I also provide a package adapted to carry suitable style and size designations sufficiently plain and large to be easily and rapidly read by the user, without requiring careful scrutiny of the needle itself to distinguish identifying marks thereon.

A further object of my invention is to produce a package which combines the various characteristics above outlined.

Other objects and advantages of my invention will be apparent from the following description, taken in connection with the accompanying drawings, in which:

40 Figure 1 is a perspective view of an envelop blank with a needle positioned thereon.

Fig. 2 is a plan view of a completed package.

Fig. 3 is a longitudinal sectional view of one form of package.

Fig. 4 is a similar view of another form.

Figs. 5 and 6 are fragmentary longitudinal sections showing additional forms of closure.

50 Fig. 7 is a transverse sectional view through a package and press.

Fig. 8 is a perspective view of a needle passed through a registering sheet, and

Fig. 9 is a perspective view of a modified form of package, parts being broken away, and in section.

I have illustrated one embodiment of my invention which includes a container formed entirely of impression-holding material, and 60 I have shown a surgical needle as the article packaged therein; but it is to be understood that my invention is not limited either to the type of container shown, nor to the package containing a surgical needle, as obviously various forms of package may be con-

structed, consisting wholly or partly of impression-holding material, and a substantial variety of articles may be advantageously packaged therein.

I have disclosed a container of the envelop type, which may be constructed from a single sheet 11, as shown in Fig. 1, folded along its median line to inclose the needle 12, the superposed edges of sheet 11 being connected to each other to form an envelop 13, as illustrated in Fig. 2. The envelop may consist entirely of a material whose distinctive characteristic is its ability to receive and retain an impression on an article in the package, such as needle 12. Such impression-holding material is also of such a nature that this impression may readily be produced in relatively permanent form by pressing the material over parts of the article which are adjacent thereto. Various materials possess these qualities, such as certain forms of prepared paper and other fibrous sheet material, gutta percha, and celluloid or other pyroxylin compounds or substitution products, when warm; but I have found that thin sheet metal, such as metal foil, is particularly suitable.

Various methods may be employed for sealing the edges of the envelop 13. In Fig. 3, I have illustrated a construction in which such edges are connected by fusion, either with or without the introduction of a suitable substance therebetween.

In Fig. 4, I have disclosed a marginal seam in which the edges are turned and pressed together to form a tight closure, either with or without suitable connecting material, such as solder or adhesive.

In Fig. 5, I have shown a marginal sealing bead 14, which may be composed of solder, spelter, wax, or other suitable substance.

In the form shown in Fig. 6, the edges are connected by a layer of adhesive 15, which may be either metallic, such as solder, or non-metallic, a great variety of such adhesives being well-known to those skilled in the art.

Heat with or without pressure may be employed in connection with the closures illustrated, as well as with other forms of closures.

The needle 12 may obviously be merely placed loosely in an envelop 13, or it may be fixed in position therein in any desired way, as by fastening it by adhesive to one or both sides of the envelop. A convenient method for maintaining the needle in a central position, in which there is a minimum of danger that the point of the needle will rupture the envelop, is to attach the needle to a positioning element adapted to be placed within the envelop 13 and to maintain the needle in its proper location when the envelop is sealed. The positioning member may be in the form of a sheet 18 of cardboard, paper or other

suitable material, and the needle may be attached thereto in various ways, as by passing the needle therethrough.

It will be apparent that while I have specifically disclosed a positioning member adapted to hold a needle in place in the package, the nature of the article which is packaged will determine the construction of the positioning member and the method of connection thereof to the article; and I do not intend to be limited to a positioning member in sheet form.

Obviously, the impression of the packaged article on the sheet 11 may be made in a great many ways, either before or after the sheet is embodied in a completed or semi-completed package. One convenient method for accomplishing this object is shown in Fig. 7, wherein the formed envelop is pressed 20 between suitable members, one of which is formed of yieldable material. It will readily be evident, however, that both of such members may be yieldable so as to produce a similar impression on both sides of the package, and also that such impression may be made on the sheet in the manner disclosed prior to the formation of the package.

The form of press shown diagrammatically in Fig. 7, includes a base 16 and a yielding pad 17 between which the envelop 13 is pressed, forcing the envelop material tightly around needle 12, regardless of its contour.

When the envelop 13 is composed of foil, it has been found that the foil will hug the needle closely, producing an accurate detailed reproduction of its exact contour, which will persist after considerable handling of the envelop, permitting the surgeon to ascertain readily and rapidly the exact 40 type of needle inclosed. As a matter of convenience in cataloguing the packaged articles, such as needles of various sizes and shapes, and in identifying individual needles in reference to such catalogues, suitable identifying marks may be placed on the envelop in any desired way, as by stamping, printing or impression. In the form illustrated 45 in Fig. 2, numerals have been impressed by suitable dies in the envelop material, denoting size and style.

While I have shown and described a single article, such as needle 12, inclosed in an individual package, it will be apparent that a number of such articles may be located 55 therein, the impression of one or more of the articles being carried by the envelop. Such needles may be placed loosely in an envelop such as that shown in Fig. 2, or they may be attached to a suitable positioning element, such as sheet 18.

Another desirable arrangement, however, is illustrated in Fig. 9, in which each needle 12, and, if desired, a positioning sheet 18, is located within a separate compartment 65 of said envelop 13. Each of said compart-

ments may be completely sealed if desired, forming practically a plurality of envelops connected in series. For this purpose, the top and bottom of the envelop may be transversely connected to form a dividing zone 70 19, any preferred method being employed to connect the top and bottom of the envelop in such zone. For instance, suitable adhesive or solder may be used, or the parts may be fused by heat with or without the employment of an intermediate flux. With this arrangement, each compartment may be separated from the others when it is desired to use the needle therein, as by severing the envelop within zone 19. If desired, 80 suitable indentations or perforations 20 may run lengthwise of each zone to facilitate separation of the compartments. A principal advantage of this construction is the facility with which a number of needles may 85 be sterilized at once in a unitary package, and each needle, sealed in its compartment, may be removed from the remainder of the package without disturbing the sealing either of such compartment or of the remaining compartments. It will be noted 90 that the separation may be readily accomplished with the scissors which are always a part of operating equipment, and which are sterilized at the same time as the 95 needles.

While packages constructed according to my invention may be manufactured in a great variety of ways, depending upon their exact nature, the specific form disclosed has 100 been so devised and arranged that it may readily be freed from internal moisture and completely sterilized. One effective method of producing this result is to place the needles within their envelops before the latter are completely sealed, and subject the embryo packages to suitable dry heat in an oven to completely drive off any vestige of moisture therein. The packages are then sealed, insuring the needles against rust regardless of the climate or repeated immersions in boiling water. While the usual boiling or other methods may be relied on for sterilizing, I prefer to sterilize the packages after they have been sealed, the claus- 105 tro-thermal method being eminently adapted to be employed for this purpose. According to this method, the sealed packages are maintained at a suitable heat, such as 160° C., for several hours, thus insuring the complete and permanent sterility of the package interior and the needles therein. This effect is substantially aided by the employment of metal foil in the container, as the foil readily conducts heat to the needle. Furthermore, the specific construction in which the foil is pressed tightly against the needle further facilitates this operation. 110 120

It will be evident that I have devised a package so constructed and arranged that it

may be handled in the standard routine of operating technique in the same way as the ordinary needle. However, my package, in the specific form disclosed, is of such a nature that it permits greatly improved technique in handling the needle at the time when it is needed by the surgeon, practically insuring complete sterility up to the moment when the needle enters the tissues.

10 In accordance with this improved aseptic technic the package is preferably sterilized in the usual way with the other instruments. When a needle is required during the operation, the surgeon or his assistant 15 with sterile hands picks up a sterile needle package and, grasping the envelop and the inclosed needle between the thumb and index finger of the left hand below the eye of the needle, tears away with the thumb and index 20 finger of the right hand enough of the envelop to expose the needle eye. Then with his sterile right hand, the surgeon or his assistant, still holding the needle protected by the major part of the foil envelop in his left hand, threads a sterile suture with his sterile 25 right hand through the eye of the sterile needle, which is withdrawn from the remainder of its envelop after threading, ready for use in stitching the wound. It will be apparent 30 that when employed in this way, my package insures the sterility of the needle up to the moment of actual use, and permits the needle to be completely threaded before the major portion thereof is exposed, eliminating 35 danger of contamination during threading and reducing to a minimum the handling of the exposed needle prior to use. However, my invention is not necessarily limited to specific envelops which are necessarily 40 adapted to be used in the exact way outlined, but includes obvious variations in construction adapted to meet special conditions.

While my package is eminently suitable for use in the fully equipped operating 45 room, it will be evident that it is also particularly advantageous for emergency operations, where the available protection against infection is scanty, as needles packaged in accordance with my invention are completely 50 sterile regardless of the treatment to which the package is subjected up to the time when the package is ruptured. Consequently, such needles may be carried on emergency calls, and used with comparative safety 55 without previous sterilization.

A further advantage of my invention is the facility with which the package may be constructed, its simplicity and compactness. While I have described my invention as 60 comprising a package, it will be apparent that such invention also includes the method of preparing the package.

Furthermore, while various materials may be employed for the envelop, I have found 65 that metal foil is particularly advantageous,

as it is readily manipulated and sealed. Moreover, it is not affected by standard methods of sterilization, and offers complete and permanent protection against moisture. In particular, however, it is especially suitable for producing and preserving the contour of the needle by pressing the foil tightly about an inclosed needle, and will likewise receive and retain the impression of style and size numbers. The foil is also readily torn to expose the needle, and facilitates an aseptic technique in handling similar to the one above outlined. Furthermore, the foil is relatively thin and compact, facilitating the packing and handling of the envelops.

While my invention, in the specific form shown, is particularly devised and adapted to surgical needles, it will be apparent that the general type shown herein is also eminently suitable for packaging a variety of other articles, both those in which it is necessary to provide a container having powers of resistance to heat, moisture, chemical action or any combination thereof, and those in which it is only necessary or desirable to employ a container carrying the outward impression of the article.

It is also noted that where sheet metal is employed for the container, such container is a conductor of electricity and permits the application of an electric current to the contents of the package for sterilizing or chemical purposes. Furthermore, surgical sutures with a needle ready threaded thereon, may be packaged in accordance with my invention, the contour of the needle being shown on the package, this arrangement providing a convenient and sterile outfit for emergency operations.

While I have described the preferred form of my invention and indicated certain variations therein, it will be apparent that many other changes may be made within the scope of my invention as set forth in this specification.

I claim:

1. A sealed package comprising a container and an article entirely inclosed therein, a portion of the container being closely pressed about the article to cause an outline of the latter to appear in relief on a surface of the package, whereby the size and contour of the article may be readily determined by an inspection of the package.

2. A sealed package comprising a container formed of flexible sheet material and an article entirely inclosed therein, a portion of the container being closely pressed about the article to cause an outline of the latter to appear in relief on a surface of the package, whereby the size and contour of the article may be readily determined by an inspection of the package.

3. A sealed package comprising a con-

- tainer formed of sheets of foil sealed together at their edges and an article entirely inclosed therein, a portion of the container being closely pressed about the article to cause an outline of the latter to appear in relief on a surface of the package, whereby the size and contour of the article may be readily determined by an inspection of the package.
- 10 4. A sterile needle package comprising a wrapper of sheet material completely inclosing a needle, the sheet material on one face of the package being pressed closely about the needle to cause an outline thereof to stand out in relief, whereby the size and contour of the inclosed needle may be readily determined upon an inspection of the package.
- 15 5. A sterile needle package comprising a wrapper of flexible sheet material completely inclosing a needle and a positioning sheet to which the needle is attached, the sheet material on one face of the package being pressed closely about the needle to cause an outline thereof to stand out in relief, whereby the size and contour of the inclosed needle may be readily determined upon an inspection of the package.
- 20 6. A sterile needle package comprising a foil sheet folded about a needle and sealed to completely inclose the same, the foil layers being in facial contact, except as to those portions in direct contact with the needle, the non-contacting portions of the sheet layers accurately defining in relief the size and contour of the inclosed needle, whereby the size and contour of the inclosed needle may be readily determined upon an inspection of the package.
- 25 7. A sterile needle package comprising 40 foil layers located upon opposite sides of and completely inclosing a needle, the foil layers being pressed in facial contact throughout their entire area, except as to those portions in immediate contact with 45 the needle, the non-contacting portions of the layers forming a replica in relief of the inclosed needle, whereby the size and shape of the needle may be determined upon inspection of the package. 50
8. A sterile needle package comprising readily separable layers of sheet material sealed at the edges only and inclosing a needle between them, the layers being pressed in facial contact throughout their entire 55 area, except as to those portions in immediate contact with the needle, the non-contacting portions of the layers forming a replica in relief of the inclosed needle, whereby the size and shape of the needle 60 may be determined upon inspection of the package.
9. A package for surgical needles and similar articles, including a container of metal foil having a plurality of sealed compartments adapted to be separated from each other without destroying the sealing of any compartment, a needle in each compartment, the foil being closely pressed about each needle so as to cause an outline of the needle 70 to appear in relief on the surface of the compartment, whereby the size and contour of the article may be readily determined by an inspection of the package. 65

Signed at New York city, in the county 75 of Kings and State of New York, this 7th day of February, A. D. 1920.

CHARLES T. DAVIS.
